UNITED STATES PATENT OFFICE.

WILLIAM UHL, OF ROCHESTER, NEW YORK, ASSIGNOR TO TODD PROTECTOGRAPH COMPANY, OF ROCHESTER, NEW YORK, A CORPORATION OF NEW YORK.

CHECK-WRITER.

1,379,425.

Specification of Letters Patent. Patented May 24, 1921.

Applictation filed September 22, 1919. Serial No. 325,503.

To all whom it may concern:

Be it known that I, WILLIAM UHL, a citizen of Germany, residing at Rochester, in the county of Monroe and State of New York, have invented certain new and useful Improvements in Check-Writers, of which the following is a specification.

This invention relates generally to machines for printing on checks and other commercial documents a limiting value to prevent them from being raised or altered and has particular reference to machines which must at all times be supplied with the proper amount of ink if they are to give the best results.

A broad object of the invention is to provide an inking mechanism which will supply and uniformly apply to the printing type the right amount of ink for them to print satisfactorily.

Another object is to provide an inking mechanism of the kind indicated which is so constructed that a liberal supply of ink of different colors can be carried in the machine with a mechanism for drawing ink from said supply and applying it to the type, the mechanism being so constructed that there is no danger of more ink leaving the source of supply than is required for the amount of work actually done.

With these and incidental objects in view the invention consists in the novel features of construction and combinations of parts, the essential elements of which are set forth in appended claims and a preferred form of embodiment of which is hereinafter described with reference to the drawings which accompany and form a part of this specification.

Of said drawings:

Figure 1 is a top view of the improved machine.

Fig. 2 is a right side view of the machine with the cover for the inking mechanism on that side removed and part of the casing broken away to expose more of the inking mechanism to view. In this figure others of the parts are shown in outline.

Fig. 3 is a section on the line 3—3, Fig. 2, looking in the direction of the arrow.

Fig. 4 is the same as Fig. 3 except that it shows the relative positions of the parts after an operation to print is commenced.

Fig. 5 is a detail of some of the improved inking mechanism. 55

Fig. 5^A is an enlarged view of some of the parts shown in Fig. 5.

Fig. 6 is a section on the line 6—6, Fig. 2, looking in the direction of the arrow.

Fig. 7 is the same as Fig. 6 except that it shows the positions of the parts after the mechanism is started to make an impression. 60

Fig. 8 illustrates the construction of one of the ink reservoirs and some of the devices associated therewith for stirring and feeding the ink. 65

Fig. 9 is a detail of one of the ink applying rollers and the parts immediately associated therewith. 70

In the drawings the invention is illustrated in the form it would take if applied to a machine of the kind fully illustrated and described in U. S. Letters Patent No. 1,138,330 issued May 4, 1915 to L. M. Todd 75 and C. G. Tiefel. Those parts of the patented machine having directly to do with the present improvement are shown and described herein and reference should be made to the patent if information as to the construction and operation of the rest of the mechanism is desired. 80

A machine of the kind shown in the patent has a type carrier which can be moved from one position to another to set any one 85 of a number of type lines in printing relation to a platen. A relative movement of the type carrier and platen is then effected to print the matter represented by the type line. The type selection is effected by 90 means of a manipulative device adjustable with reference to an index suitably marked to guide the operator in positioning the type carrier.

In order to make it difficult to alter words 95 or characters so printed, the type and platen have their coöperating faces constructed to disrupt the fibers of the paper printed upon. This, in connection with a pressure applied to the paper by the type and platen, incorporates the ink with the fiber of the paper, thereby making erasure difficult. In addition to this, certain of the words or characters are printed in different colors to make it additionally difficult to effect alterations, 100 particularly if an alteration involves the 105

printing of a new amount over the old one. The improved machine has a reservoir for each kind of ink and associated with each reservoir is what may properly be termed 5 a force pump which is preferably operated once during a number of printing operations to draw a supply of ink from the reservoir and force it to the devices for applying it to the faces of the type. Controlling mechanism is provided which prevents actuation 10 of a pump when the printing employs ink of a different color.

Describing the machine in detail and with reference to the drawings, part of the mechanism is inclosed in a base 11 and the rest in a top 12 hinged at 13 to the base. Latches (not shown) coöperate with the hinges when the top is closed to prevent movement of the top relative to the base during printing 20 operations. The top of the base 11 is suitably constructed to serve as a printing bed or table for the work and the hinged top is cut away as shown at 14, Fig. 2, to provide a slot through which the work can 25 pass on its way through the machine. The hinged top is provided with a shield 15 (Fig. 4) inclosing the mechanism contained in the top, this shield being provided with an opening through which type described in 30 detail later on can coöperate with a platen 16. The platen 16 is carried in a swinging frame or bracket 17 which is moved to carry the platen 16 toward and from the type carrier as described in the Todd and Tiefel 35 patent. The type 18, Figs. 2, 3 and 4, are arranged in circumferential rows on the periphery of a plate 19 attached to the face of an element comprising portions 20 loose on a shaft 21 and connected together by a 40 portion 22 which has its outer face concentric to the shaft.

The portion 22 is provided with a rib 23 engaging a longitudinal groove in the shaft 21 thereby permitting the shifting of the 45 type carrier along the shaft to different positions while rotation of the shaft relative to the carrier is prevented.

Loose on the shaft 21 and adjacent to the ends of the type carrier are the arms of 50 a yoke 24 provided with a handle 25 whereby the yoke and the type carrier may be shifted to different positions along the shaft 21. This shifting movement is to bring any type line 18 opposite the platen 16, a 55 pointer 26 (Fig. 1) and scale 27 being provided to guide the operator. After the desired line of type is positioned opposite the platen the shaft 21 is given a complete rotation, thereby carrying the selected line 60 of type over the platen to print the matter represented by the type.

The connections for rotating the shaft 21 include a short shaft 28 journaled in a boss 29 on the top 12 of the casing. Attached 65 to the inner end of the shaft 28 is a small

gear 31 meshing with a gear 32 rigid with the shaft 21, the gears 31 and 32 being of the same size so that each full turn of the handle 25 will effect a complete rotation of the shaft 21.

It is clear that using the machine to write an amount the handle 25 is adjusted to different positions with reference to the scale 70 27 and at each position the operating handle 30 is turned, thereby causing the shaft 21 75 and carrier to turn and coöperate with the platen 16 to print the desired word. This is repeated until the words and characters necessary to complete the inscription have 80 been printed. The type selecting movement 85 of the handle 25 not only determines the words to be printed, but it also determines the color of the printing and controls the inking mechanism previously referred to and hereinafter described in detail.

The inking mechanism comprises two rolls 33 and 34, Figs. 3 and 4. In machines of this kind the two colors preferred are red and black and in the present instance the roll 33 is for the black ink and the other for 90 the red. The ink rolls are rotatable on studs 35 (see also Fig. 9) on arms 36 and 37 attached respectively to shafts 38 and 39. These shafts are journaled at their forward ends in brackets 40 on the inside of 95 the top and at their rear ends are journaled in and extend beyond the casing.

Pivoted to the sides of the arms 36 and 37 are small arms 41 with laterally formed portions 42 holding small brushes 43 for 100 distributing the ink on the surfaces of the ink rolls 33 and 34. Torsion springs 44 hold the arms 41 in proper relation to the supporting arms 36 and 37. It will be noted that there is some difference in the shapes 105 and relative positions of the arms 41 and the arms 36 and 37 but these differences are, for the present purpose, immaterial, the main reason for them being to permit the roll 33 to contact the type as early in the 110 rotation of the shaft 21 as possible.

Formed substantially at right angles to the arms 36 and 37 respectively are ears 45 and 46 upon which are rotatably mounted rollers 47 and 48. These rollers coöperate 115 respectively with portions 51 and 52 (Fig. 1) of a controlling plate 56 (see also Figs. 2, 3 and 4) attached to the underside of the longitudinal bar of the yoke 24. This controlling plate coöperates with the rollers 47 120 and 48 to determine whether the inking roll 33 or 34 is to be swung to inking position.

Fastened respectively to the shafts 38 and 39 at the rear end of the machine are levers 53 and 54 (Figs. 6 and 7) connected by a 125 spring 55 tending at all times to draw the lower ends of the levers toward the shaft 21 and thereby rock the shafts 38 and 39 to swing the ink roll arms 36 and 37 into the path of the type. As shown in Fig. 6, 130

this movement of the levers is normally prevented by engagement of rollers on the levers with cams 56 and 57 rigid with the shaft 21. These cams are so formed that at 5 their home or normal positions they hold the levers 53 and 54 apart a sufficient distance to hold the rollers 47 and 48 out of contact with the coöperating portions of the plate 56 so that there will not be even a slight interference with the movement of the 10 yoke 24 to different positions in selecting the type to be printed.

When the shaft 21 begins to turn to effect engagement of the type and platen to print 15 the cams 56 and 57 are, as shown in Fig. 7, carried out of the paths of the rollers on the levers 53 and 54. This renders the spring 55 effective to swing one of the levers and rock the associated inking arm 36 or 37 to 20 position its ink applying roller in the path of the type. Movement of the other lever will always be instantly arrested by engagement of the corresponding roller 47 or 48 with the coöperating portion 51 or 52 of 25 the controlling plate 56 and the arrested inking arm will be held in a position where its roller cannot contact the type. It is apparent that the movement of the controlling plate 56 as an incident to selecting the type 30 will control the ink applying devices so that they will apply ink only to the proper sections of the type plate, thereby preventing any confusion of colors through accidental application of ink of different colors to the 35 same line of type.

The ink is supplied to the rollers 33 and 34 through conduits 61 and 62 having their lower ends positioned to deposit ink on or adjacent to the distributing brushes 43. 40 These conduits are supported in bosses 63, (Fig. 5) integral with the casing. The upper ends of the conduits pass through suitable holes in elements 64 (see also Fig. 5^A) threaded to screw into the casing of the 45 machine, gaskets 65 surrounding the ends of the conduits and being compressed sufficiently to give an ink tight connection. In alinement with the upper ends of the conduits are small holes 66 extending into tubular openings 67 drilled or otherwise formed 50 in the casing 12. The forward ends of the tubular openings 67 are closed by screws 68. The portion of the tubular opening or chamber adjacent these screws contains a 55 cushion or buffer 69, the purpose of which will be explained later. Mounted in the tubular openings 67 are shafts 71, these shafts having an endwise movement.

Extending around the shaft 71 is a circumferential groove 72 (Fig. 5^A) and drilled or otherwise formed in the end of the shaft is a hole 73. The reduced portion of the shaft at the bottom of the circumferential groove 72 is provided with four holes 74 extending radially of the shaft and with their

inner ends terminating at the hole 73. The shaft 71 is reciprocated by mechanism described later, carrying the circumferential groove from one position to another so that it will successively pass a hole 75 extending 70 into the interior of an ink reservoir 76 and the hole 66 in alinement with the upper end of the conduit.

The shaft 71 fits snugly in the opening 67 and if it is moved, for example, from the position in which it is shown in Fig. 5 toward the right, a partial vacuum will be created in the part of the opening 67 adjacent the left end of the shaft so that when the circumferential groove 72 comes in alinement with the opening 75, the partial vacuum will cause ink to be drawn from the reservoir 76. At the same time the partial vacuum will be destroyed. When the shaft moves in the opposite direction, that is, toward the left in Fig. 5, the circumferential groove 72 will be carried out of register with the opening 75 and carry with it the ink just drawn from the reservoir. As the circumferential groove passes out of register 90 with the hole 75 the ink in the groove, holes 74 and 73 and the chamber or opening adjacent the left hand end (Fig. 5) of the shaft, will be gradually compressed until the groove is brought into alinement with the 95 opening 66 and upper end of the conduit. Then the compression will be released and the ink forced down into the conduit tube.

The cushion 65 is to relieve the mechanism from strain because of the compression 100 becoming too great. When the amount of compression becomes great enough, the spring behind the cushion will yield until the compression is released, whereupon the spring will return the cushion plunger to 105 its original position. The space between the cushion plunger and the end of the screw 65 connects with the reservoir by means of a passage 77 so that when the cushion is moved to relieve compression, the movement 110 will not be interfered with by any compression between the cushion and the screw.

The mechanism is so constructed that a number of operations to print in one color are necessary to effect a complete reciprocation of the corresponding shaft 71. The mechanism for effecting the reciprocation comprises a rotary member 81 (Fig. 2) journaled in an extension of the casing. The end of the member 81 is drilled to receive a reduced portion of the shaft 71, the connection being such that the shaft 71 may move freely endwise relative to the shaft 81. 120

Formed around the member 81 is a cam groove 82 coöperating with one end of the pin fastened in an arm 83. The other end of the pin coöperates with a straight groove 84 in the underside of a boss on the casing. The arm 83 is clamped to the shaft 71 by means of lock nuts 85 and the groove 84 130

coöperates with the pin in the arm in such a way as to prevent rotation of the shaft 71. The lock nuts may be shifted along the shaft 71 to give the arm 83 different positions on the shaft in order to get the proper coöperation of the circumferential groove 72 (Fig. 5^A) in the shaft with the passage 75 and conduit. The cam groove 82 is so formed that when the member 81 makes 10 a complete rotation the shaft 71 will have been given a complete to and fro movement to withdraw ink from the associated reservoir and force the ink toward the ink applying roller.

15 The mechanism for effecting rotations of the members 81 is actuated by the levers 53 and 54 previously described. Pivoted to the upper ends of these levers are pawls 86 and 97 connected by a spring 88. These 20 pawls have laterally extending portions 89 (Fig. 8) coöperating with the teeth of ratchet disks 90. When the cams 56 and 57 are carried out of effective position the consequent movement of the lever 53 or 54, 25 whichever is freed by the controlling plate 56, will swing under the influence of the spring 55 as previously described and carry the laterally extending portion 89 of the corresponding pawl idly over the teeth of its ratchet disk 90. When, during the latter 30 part of the printing movement of the shaft 21, the associated cam 56 or 57 restores the lever to its normal position, the portion 89 of the pawl will engage the teeth of the 35 ratchet disk 90 and turn the disk slightly. Retaining springs 91 coöperate with the teeth of the ratchet disks to prevent reverse movement.

It is clear that after a number of operations, for example, of the pawl 86 the 40 associated member 81 will have made a complete rotation with a corresponding complete reciprocation of the shaft 71.

The ink used in machines of this type 45 is of such a nature that it must be agitated or stirred to prevent it from settling and caking. It is particularly important that this be done where the ink must flow through small passages. The illustrative machine 50 includes a device which both stirs the ink in each reservoir and advances it toward the passage through which it leaves, although this mechanism is not a part of the present invention. The reservoirs are, as shown in 55 Fig. 8, tubular in their form and journaled in each of them is a shaft 93. Secured to and surrounding the shaft 93 is a wire helix 94 suitably formed to stir the ink and advance it toward and across the end of the 60 opening or passage 75. Fastened to the outer end of the shaft 93 is a gear 95 meshing with a gear 96 integral with the ratchet disk 90. It is apparent, of course, that when the ratchet disk is operated the cor-

responding shaft 93 will be turned to cause 65 the wire helix to do its work. The gears 95 and 96 are both larger than the ratchet disk 90 so that the helix 94 will have enough movement to keep the ink well mixed. If preferred, the shafts 93 may be driven by a 70 gear connection directly with the shaft 21 arranged to give the helix a greater extent of movement at each operation than is the case with the mechanism shown in the drawings.

75 While the form of mechanism herein shown and described is admirably adapted to fulfil the objects primarily stated, it is to be understood that it is not the intention to limit the invention to the one form, as it 80 is susceptible of various changes and modifications, all of which come within the scope of the claims which follow.

What I claim is:

1. In a machine of the class described, 85 the combination with a printing couple, of an ink reservoir, means comprising a member having a reciprocatory movement for drawing ink from the reservoir and feeding it to the printing couple, a movable element 90 provided with a cam groove, a pin engaging said groove and rigid with the reciprocatory member, and means for actuating said movable element by operations of the printing couple.

95 2. In a machine of the class described, the combination with a printing couple, of an ink reservoir, means comprising a member having a reciprocatory movement for drawing ink from the reservoir and forcing it 100 toward the printing couple, a rotatable element provided with a cam groove, a pin engaging said groove and rigid with the reciprocatory member, and means for effecting a rotation of said rotatable element by 105 a plurality of operations of the printing couple.

110 3. In a machine of the class described, the combination with a printing couple, of an ink reservoir, means comprising a plunger having a rectilinear to and fro movement for drawing ink from the reservoir and forcing it toward the printing couple, a rotatable element provided with a cam groove, 115 a connection rigid with the plunger and engaging said groove, and means requiring a plurality of operations of the printing couple for effecting a complete rotation of the rotatable element.

120 4. In a machine of the class described, the combination with a printing couple, of an ink reservoir, means comprising a plunger having a rectilinear to and fro movement for drawing ink from the reservoir and forcing it toward the printing couple, a rotatable member provided with a cam groove, 125 an element engaging the cam groove and adjustably secured to the plunger, and

means requiring a plurality of operations of the printing couple for effecting a complete rotation of the rotatable member.

5. In a machine of the class described, the combination with a printing couple, of an ink reservoir, pump mechanism for drawing ink from the reservoir and forcing it to the printing couple, said pump mechanism comprising a compression chamber, and a 10 cushion device movable relative to the compression chamber to relieve the mechanism from excess strain in effecting the compression.

6. In a machine of the class described, the combination with a printing couple, of an ink reservoir, pump mechanism for drawing ink from the reservoir and forcing it to the printing couple, said pump mechanism comprising a compression chamber, a cushion 20 device movable relative to the compression chamber to limit the amount of compression, the wall of the reservoir being provided with a passageway extending to a position adjacent the cushion to prevent compression on one side of the cushion.

7. In a machine of the class described, the combination with a printing couple, of an ink reservoir, pump mechanism for drawing ink from the reservoir and forcing it to the 30 printing couple, said pump mechanism comprising a compression chamber, a cushion element movable relative to the compression chamber, a spring normally holding said element in position and permitting movement of the element to relieve excess compression, the reservoir being provided with a passageway extending to a position adjacent the spring.

8. In a machine of the class described, the combination with a plurality of ink reservoirs for inks of different colors, of a force pump associated with each reservoir for pumping ink from the reservoir and forcing it toward the printing couple, a cam for operating each pump, a manipulative device adjustable to different positions to control the matter printed by the printing couple, and devices controlled by said manipulative device for selectively rotating the cams.

50 9. In a machine of the class described, the combination with a printing couple, of an ink reservoir, means comprising a plunger having a rectilinear to and fro movement for drawing ink from the reservoir and forcing it toward the printing couple, a rotatable member provided with a cam groove, an arm adjustably clamped to the plunger and extending parallel to the plunger and beyond the cam groove, a pin carried by the arm

with one end thereof engaging the cam 60 groove and the other end coöperating with a slot running parallel to the plunger to prevent rotation of the plunger, and means requiring a plurality of operations of the printing couple for effecting a complete rotation of the rotatable member.

10. In a machine of the class described, the combination with a printing couple, of an ink reservoir, means comprising a plunger having a rectilinear to and fro movement for drawing ink from the reservoir and forcing it toward the printing couple, a rotatable member provided with a cam groove and drilled at one end to receive a reduced portion of the movable plunger, an arm adjustably clamped to the plunger and extending parallel to the plunger and beyond the cam groove, a pin carried by the arm with one end thereof engaging the cam groove and the other end coöperating with a slot 70 running parallel to the plunger to prevent rotation of the plunger, and means requiring a plurality of operations of the printing couple for effecting a complete rotation of the rotatable member.

85 11. In a machine of the class described, the combination with a printing couple, of an ink reservoir, means comprising a plunger having a rectilinear to and fro movement for drawing ink from the reservoir 90 and forcing it toward the printing couple, a rotatable member provided with a cam groove and slidably supporting one end of the plunger, an arm adjustably clamped to the plunger and extending parallel to the plunger 95 and beyond the cam groove, a pin carried by the arm with one end thereof engaging the cam groove and the other end coöperating with a slot running parallel to the plunger to prevent rotation of the plunger, and means requiring a plurality of operations of the printing couple for effecting a complete rotation of the rotatable member.

100 12. In a machine of the class described, the combination with a printing couple, of an ink reservoir, mechanism for drawing ink from the reservoir and forcing it to the printing couple, said mechanism comprising a compression chamber, said chamber having a passageway extending to the reservoir, a cushion device movable relative to the compression chamber to relieve excess compression, and the reservoir having a passageway extending to a position back of the cushion to relieve compression back of the cushion.

115 In testimony whereof I hereby affix my signature.

WILLIAM UHL.
